UNITED STATES PATENT OFFICE.

PAUL E. THOMPSON, OF WORLAND, WYOMING.

CANVAS DAM.

1,380,439.

Specification of Letters Patent.

Patented June 7, 1921.

Application filed July 11, 1919. Serial No. 310,141.

To all whom it may concern:

Be it known that I, PAUL E. THOMPSON, a citizen of the United States, residing at Worland, in the county of Washakie, State 5 of Wyoming, have invented certain new and useful Improvements in Canvas Dams; and I do hereby declare the following to be a full, clear, and exact description of the invention, such as will enable others skilled in the art 10 to which it appertains to make and use the same.

This invention relates to an improved dam for irrigating purposes and particularly to a type constructed of canvas particularly adapted for use in small laterals or ditches in the fields, for directing the flow of water over on the land to be irrigated. The invention contemplates an improved construction of canvas dam which will over- 20 come the objections consequent upon the use of a long strip of canvas as has been in common use but which can only be used with efficiency where there is a small head of water and where the means for anchoring 25 or holding the canvas in the ditch is very inefficient and therefore will not permit the dividing of the water so as to deflect it in the desired course.

The invention further contemplates an improved canvas dam having means to support it across a ditch or lateral with the supporting means resting upon the ground at the side walls thereof. The dam includes a frame serving as means for anchoring a 35 sheet of canvas whereby to resist the pressure of the water, while novel means are provided for anchoring the edge of the canvas. The anchoring means is an apron adapted to be embedded in the mud or sand 40 of the bottom and side walls of the ditch or to have dirt packed upon it, whereby to form an efficient seal to prevent the water from breaking through. There is also provided a gate to entirely close off the flow of 45 water or to permit regulation of the quantity of water passing through depending upon the requirements for proper irrigation of the land and thus the volume of water which it is necessary to deflect into a lateral 50 for the purpose stated.

A further object of the invention is to provide a canvas dam which is adapted to be set at an angle of 45 degrees so as to relieve the device of the pressure of the 55 water tending to break it down and which embodies a blank section of canvas of novel

outline for the purpose of producing means to attach the canvas to its supporting and retaining means and also for producing a gate adapted for regulating the flow of the 60 water as previously set forth.

With the above objects and the others in view, as will be more fully appreciated and understood as the specification proceeds, the invention comprises certain novel combina- 65 tions and arrangements of parts as will be hereinafter more particularly described, and pointed out in the claims.

Reference is had to the accompanying drawings forming a part of this application, 70 wherein like reference characters designate corresponding parts throughout the several views, wherein:

Figure 1 is a plan view of my improved irrigating dam in applied position; 75

Fig. 2 is a front elevation thereof taken across the ditch or lateral;

Fig. 3 is a rear elevation;

Fig. 4 is a vertical sectional view, and

Fig. 5 is a horizontal sectional view. 80

Referring to the drawings in detail, my improved dam comprises a supporting bar 10 of sufficient length to bridge the walls of a ditch indicated at D, and from which a lateral L extends, the bar being designed 85 to support the dam in the ditch at a point remote from the lateral. The bar serves to support a canvas sheet 11 which is shaped according to the cross sectional outline of the ditch in order to conform to the walls 90 thereof and permit sealing of the dam against said walls.

As illustrated, the canvas sheet is of substantially semi-circular outline and has its rectilinear edge suitably anchored to the 95 bar 10 as by means of a securing strip 12, the canvas sheet being disposed between the bar and the strip and the strip being suitably secured to the bar as indicated at 13 so as to resist detachment from the pressure 100 or head of water. The blank section of canvas is cut out as indicated at 14 to provide a semi-circular or other desired shape of opening, constituting means of permitting the overflow or discharge of excess 105 water above that volume required to be deflected into the lateral for efficient irrigation of the land. The material thus cut out forms a flap 15 which constitutes part of a gate 16 which it reinforces at the opening. 110 The gate 16 also comprises a section of canvas suitably stitched or otherwise secured

to the flap and to the sheet 11 along the top edge of the opening so as to overlie the surrounding edge of the opening 14 and resist the passage of water therethrough. 5 To facilitate this, the edge of the opening is reinforced with a binding indicated at 17 and the lower edge of the gate is provided with a hem 18 formed by turning and stitching the material thereof so as to inclose a 10 substantially U-shaped stiffening member 19 of wire or other suitable material designed to render the gate rigid and prevent it from being forced through the opening by the pressure of the water. The gate however 15 can be opened any desired degree and held in an open position by suitable means such as an adjustable hook and chain connection 20' coöperating with the bar 10. By this means, if all of the water is not desired in 20 the lateral, it may be allowed to overflow through the opening and continue in the ditch D for irrigating other land.

As means for anchoring the canvas sheet, there is suspended from the bar 10 a frame 25 20 of an outline corresponding to the outline of the canvas sheet and shown to be of U-shape with the extremities thereof passed vertically through the bar 10 and held by anchoring means 21. By so anchoring the 30 frame, it is held rigid with the bar and is preferably extended at an angle of about 45 degrees in the direction from which the water flows, so as to better resist the pressure thereof. The frame is reinforced by 35 an intermediate bracing bar 22 also anchored to the bar 10 in the same manner as the extremities of the frame and connected to the extreme lower portion of the frame so as to be disposed vertically in front of 40 the gate. While the bar 22 may be suitably anchored to the frame it is shown in the preferred embodiment illustrated herein, as having its lower end coiled around the material of the frame as indicated at 23 so as 45 to extend rigidly between the frame and the bar 10. There is also secured to the face of the canvas sheet a hem 24 formed by a strip of material folded on itself and stitched or otherwise secured to the sheet 50 so as to house the frame therein and thereby prevent the sheet from pulling away under the pressure of the water. If desired the sheet can be slightly gathered adjacent to the extremities to the frame so as to form 55 a pocket within the frame of the canvas attached thereto. The canvas sheet is somewhat larger than the metal frame to which it is secured and its margin projects beyond

the frame to constitute an apron 25. The apron is forced into the mud or sand, or 60 a few shovels of loose dirt or mud are thrown on to it, thereby preventing the water from escaping around the device. It is also to be understood that the device is to be made in various sizes depending upon 65 the cross sectional dimensions of the ditch and that instead of canvas, any desired flexible water-proof material of proper strength, may be employed, and that the device may be used at any desired point to 70 regulate or deflect the flow of water.

What is claimed is:

1. A dam for irrigating ditches comprising a bridge bar having a U-shaped frame depending therefrom and a strip of fabric 75 looped about the frame, a fabric sheet to which the edges of the strip are stitched, the sheet extending beyond the frame continuously of it below the bar and constituting a sealing apron flexible at all points.

2. A dam for irrigating ditches comprising a frame including a U-shaped rod, a strip looped about the rod continuously and a fabric sheet to which the edges of the strip are stitched, the sheet extending beyond the frame as an apron, flexible at all 85 portions.

3. A dam for irrigating ditches comprising a bridge bar, a U-shaped frame rod depending from the bar and deflected at its 90 lower portion out of the vertical plane of the bar, a brace rod connecting the intermediate portions of the bridge bar and frame, and a fabric sheet secured to the frame and bar.

4. A dam for irrigating ditches comprising a bridge bar, a U-shaped frame having its end portions engaged upwardly through the bar, the frame depending from the bar and deflected below the bar out of the vertical plane of the bar, a fabric sheet secured 100 at its upper edge to the longitudinal face of the bar from which the frame is deflected and having its remaining marginal portions connected with the frame, the sheet 105 having an opening through its upper portion, a gate carried by the sheet between it and the frame, and means for connecting the gate to the brace when the gate is in open position, to hold it so.

In testimony whereof, I affix my signature, in the presence of two witnesses.

PAUL E. THOMPSON.
